UNITED STATES PATENT OFFICE.

WILLIAM L. WEBER, OF TAYLORVILLE, ILLINOIS, ASSIGNOR TO RAILWAY AND MINE SUPPLY COMPANY, OF CHICAGO, ILLINOIS, A CORPORATION OF ILLINOIS.

CAR-WHEEL MOUNTING.

1,285,509.

Specification of Letters Patent. Patented Nov. 19, 1918.

Application filed July 11, 1918. Serial No. 244,343.

To all whom it may concern:

Be it known that I, WILLIAM L. WEBER, a citizen of the United States, residing at Taylorville, in the county of Christian and 5 State of Illinois, have invented certain new and useful Improvements in Car-Wheel Mountings, of which the following is a specification.

This invention relates to the general art 10 of railway cars, and has reference more particularly to mine cars. Owing to the sharp curves of the tracks on which mine cars travel, it is necessary to mount the wheels of mine cars rotatably upon the axles, and further to provide means for preventing end- 15 wise displacement of the wheels from the axles. In one type of mine cars the wheel is attached to the axle, and in another the wheel is attached to the bearing box of the 20 axle. My present invention relates to cars of the latter type, and among the objects of the invention are to provide an improved means for attaching the wheel to the bearing box that shall permit the wheel to be 25 readily removed when necessary without disturbing either the axle or the bearing box; to provide such an attaching means which shall have the further function of protecting the joint between the wheel hub and the 30 bearing box from dust and dirt; and to provide an improved means for holding a lubricant and distributing the same to the wheel bearings.

Other objects and advantages of the invention will be apparent to those skilled in the art from the following detailed description, taken in connection with the accompanying drawing in which I have illustrated a practical and workable embodiment of the 40 invention, and wherein—

Figure 1 is a vertical section through the bearing boxes and wheels of a mine car in the plane of the axis of the axle, the figure being broken out between its ends;

45 Figs. 2 and 3 are transverse sections on the lines 2—2 and 3—3 of Fig. 1, respectively;

50 Fig. 4 is a detail elevation of one of the detachable devices for locking the wheel to the bearing box and protecting the joint between said parts;

Fig. 5 is a fragmentary view of a modified form of end thrust washer; and

Fig. 6 is a face view, and Fig. 7 an en-

larged section on line 7—7 of Fig. 6 of another modified form of end thrust washer. 55

Referring to the drawings, 5 designates the floor of the car body, to the underside of which are strongly secured by bolts 6 (Fig. 3) a pair of oppositely disposed bearing boxes 7 which are formed with axially aligned bearing openings 8 which receive the axle 9. Between the inner opposed ends of the bearing boxes 7, and connecting the latter, is a tubular member 10, the axis of which 60 preferably, and as shown, coincides with the axis of the bearing openings 8 and the axle 9. This tubular member 10 constitutes an oil receptacle or holder, and as herein shown its two ends are entered into the proximate 65 ends of the bearing boxes for some distance, and to provide a strong and rigid connection the ends of the members 10 are threaded, as shown at 10', or otherwise roughened, and the bearing boxes 7 are cast thereon. The 70 walls of the bearing openings 8 of the boxes 7 are provided with one or more longitudinally extending grooves 11, located at the bottom of the box or in any other desirable 75 position, the inner ends of which communicate with the oil holder 10, and the outer ends of which open through the outer ends or faces of the bearing boxes 7. 80

On the projecting ends of the axle 9 are roller bearings 12 carried by cages 13 and 85 surrounded by a hardened steel bushing 14 which latter fits within the hub 15' of the wheel 15, it being noted that the outer end of the hub is closed by a transverse wall 16. Between the inner end of the hub 15' and the 90 outer end of the bearing box 7 are interposed a plurality of metal washers 17 which receive the wear of the end thrust of the hub; and encircling the axle 9 within the washers 17 is another metal washer 18 which, as best 95 shown in Fig. 2, is preferably of substantially rectangular external form so as to leave spaces or openings 19 between its outer periphery and the inner periphery of the washers 17 for the flow of oil to the latter 100 and to the bearings of the wheel. This provision for oil flow contributes greatly to the smooth and prolonged successful operation of the wheel.

Furthermore, this square washer serves to 105 maintain the thrust washers in operative position always outside the perimeter of the ball bearing cage 13 and since the aggregate

thickness of the thrust washers is greater than the thickness of the square washer, any liability of end thrust being imparted to the cages, such as would tend to bind, twist or 5 distort the cages is entirely obviated by the square washer.

Secured to the inner side of the wheel 15, preferably by means of through-bolts 20, is a locking member which takes the form of a 10 ring 21 made in mating halves and provided with radial attaching lugs 22 through which the bolts 20 pass and with an in-turned flange 23. This flange 23 overlaps an annular shoulder 24 that is formed on the outer 15 end of the bearing box 7, so that the wheel is thereby securely locked to the bearing box against endwise displacement from the axle. At the same time the body of the ring 21 constitutes a housing which completely covers 20 the joint between the hub and the bearing box and protects the same from the entrance of dust, dirt and other foreign matter that is readily attracted by the oil flowing across said joint to the washers and 25 roller bearings.

It should be observed at this point that the bolts 20 pass through the spokes of the wheel so as to offer no obstruction to spragging as customarily practised in the mines. 30 Spragging is further facilitated by the rounded formation of the outer end of the hub and the spaces between the spokes, as will be evident from the drawings.

The tubular oil container 10 is provided, 35 between the inner ends of the bearing box 7, with an opening 25 closed by a plug 26, through which lubricant may be supplied by withdrawing the plug and attaching the nozzle of an oil can or grease gun. The oil or 40 grease flows readily through the grooves or ducts 11 to the outer ends of the bearing boxes, flowing thence through the spaces 19 between the inner and outer washers to the roller bearings of the wheel and at the same 45 time thoroughly lubricating the washers themselves, thereby reducing the wear of said parts which are subjected to the end thrusts of the hub and roller bearings.

In the form of end thrust washers shown 50 in Fig. 5 the two outer washers 17' are of hardened steel while the intermediate one 17" is equipped with hardened balls 27 projecting beyond the outer faces of the washer so as to be engaged by the other washers 55 thereby affording a ball bearing end thrust bearing. Instead of using a plurality of washers to take the end thrust, I may use a single washer 28 (Figs. 6 and 7) formed with holes 29 and with oil ways or channels 60 31 leading from the inner periphery of the washer on both sides of the latter to said holes for the purpose of distributing lubricant. Obviously other arrangements of thrust bearing might be resorted to to secure 65 the same results.

With further reference to the tubular member or pipe 10, it is noted that not only does the annular space between the axle and the pipe provide an oil reservoir but said pipe maintains alignment between the bearing boxes and the wheel bearings, imparts great rigidity to the structure, and prevents the bending of the axle which is a most common trouble in coal mine pit cars. 70

It is believed that the foregoing description, in connection with the drawings, will make clear to those familiar with this art how the stated objects and advantages of the invention are obtained in the structure illustrated and described. Manifestly changes in 75 the detail structure and arrangement of the parts may be made without altering the substantial character of the invention or sacrificing any of the advantages thereof, and hence I reserve all such variations and modifications as fall within the spirit and purview of the appended claims. 80

I claim:

1. In a car wheel mounting, the combination of an axle, an axle bearing-box formed 90 with an annular shoulder, a wheel mounted on said axle, a locking member carried by said wheel and formed with a flange overlapping said shoulder and coöperating with the latter to prevent displacement of said 95 wheel endwise of said axle and means accessible on the outer face of the wheel for detachably securing said locking member to the wheel. 100

2. In a car wheel mounting, the combination of an axle, an axle bearing-box formed with an annular shoulder, a wheel mounted on said axle, a locking ring detachably secured to the inner side of said wheel and formed with an in-turned flange overlapping said shoulder and a thrust washer between the wheel hub and the bearing box for preventing end thrust on said axle. 105

3. In a car wheel mounting, the combination of an axle, an axle bearing-box formed 110 with an annular shoulder, a wheel mounted on said axle, a locking ring formed in mating halves each provided with an in-turned flange overlapping said shoulder, and through-bolts securing said locking ring to 115 the inner side of said wheel and accessible for detachment from the outer face of the wheel. 120

4. In a car wheel mounting, the combination of an axle bearing-box, an axle mounted therein and having a projecting end, a wheel having a hub surrounding the projecting end of said axle, roller bearings between said hub and axle, an annular washer between the inner end of said hub and the opposed end of said bearing-box, and another washer 125 encircling said shaft within said annular washer and lying between the inner end of said roller bearings and the opposed end of said bearing-box. 130

5. In a car wheel mounting, the combination of a bearing-box, an axle mounted in said bearing-box and projecting beyond the outer end of the latter, a wheel having its hub journaled on the projecting end of said axle, a plurality of washers encircling said axle between the inner end of said hub and the outer end of said bearing-box and a polygonal washer interposed between said washers and said axle.
6. In a car wheel mounting, the combination of a bearing-box, an axle extending therethrough, a wheel journaled on said axle, roller bearings interposed between said wheel and said axle, a thrust device interposed between the end of said axle and the inner end of the wheel hub, and a washer of less thickness than said thrust device encircling said axle in longitudinal alinement with said roller bearing and serving to maintain said thrust device in position.
7. In a car wheel mounting, the combination of a bearing-box, an axle extending therethrough, a wheel journaled on said axle, roller bearings interposed between said wheel and axle, a thrust device disposed between the wheel hub and said bearing-box, and means carried by said axle for maintaining said thrust device out of alinement with said roller bearing.
8. In a car wheel mounting, the combination of a bearing box, an axle disposed therein, a wheel mounted upon roller bearings upon said axle, a thrust device interposed between said bearing box and said wheel hub, and means for maintaining said thrust device out of longitudinal alinement with said roller bearings to prevent end thrust from being exerted on said roller bearings.
9. In a car wheel mounting, the combination of a pair of bearing-boxes alined to receive an axle, an axle extending therethrough, a metal pipe rigidly connected at each end to said boxes to maintain the same in alinement, wheels mounted upon said axle outside said boxes, and means interposed between said wheels and their boxes whereby end thrust of the wheels is transmitted to the rigidly connected boxes and is prevented from being transmitted to said axle.

WILLIAM L. WEBER.
